UNITED STATES PATENT OFFICE.

JOHN S. BIRCH, OF NEW YORK, N. Y.

CENTER-BOARD FOR VESSELS.

SPECIFICATION forming part of Letters Patent No. 292,890, dated February 5, 1884,

Application filed December 29, 1882. (No model.)

To all whom it may concern:

Be it known that I, JOHN S. BIRCH, a citizen of the United States, residing at New York city, in the county and State of New York, have invented new and useful Improvements in Center-Board Vessels, of which the following is a specification.

In this improvement in center-board vessels it is designed to use a center-board having more of the form and qualities of a keel by reason of greater length and less depth than the common center-boards; and the invention consists of an arrangement of inclined ways for its support, and on which it may be raised and lowered, so that while it is made to rise and fall about in the same measure throughout its whole length, instead of swinging, as most center-boards do, the power to raise it needs only to equal about half the weight of the board, and the resistance is no more in any part of its rise than another, so that the power that is competent for moving it in any part of its course is sufficient for all parts.

In order that the center-board may project to a greater extent aft than forward, whether partly or wholly down, and that such greater extension shall be proportionately the same, whether the center-board be wholly or partly down, the ways on which the center-board rises and falls are varied as to their inclination, the angles of the forward ways being less than those aft—that is to say, if it be desired that the extension of the keel be three feet aft and two feet six inches forward when wholly down, the inclines shall so vary in the angles that when half down the aft end will extend one foot six inches, and the forward end one foot three inches, and so on. The essential object of this arrangement is that weight applied to the lower edge of the center-board for ballast shall bear the same relations to the line of the center of gravity of the vessel (which rises from stern to bow) from end to end of the center-board, whether it is wholly or partly extended.

Figure 1 is a longitudinal section of the hull of the vessel along the center-board space, showing my improved arrangement of the center-board, the said board being partly lowered to the bottom of its range. Fig. 2 is a similar view, showing the center-board lowered at the

stern and raised at the bow, as my improved arrangement enables it to be, for favoring the tacking of the vessel about. Fig. 3 is a transverse section of the hull of the vessel, taken on the line *x x* of Fig. 1. Fig. 4 is a detail in section on the line *y y*, Fig. 1, and Fig. 5 is a partial longitudinal section, showing the application of a signal apparatus, as I propose to indicate the rise of the center-board by riding on shoal bottom.

I propose to make a center-board space, *a*, along the vessel nearly from stem to stern, enclosed by two partitions, *b*, cover *c*, and the end sections, *d*, said space opening through the bottom of the vessel, the two sides of which are to be connected across said space at suitable intervals along it by strong bolts *d'*, passing through the timbers *e*, in which they are fastened by screw-threads *f*, shoulder *g*, and nuts *h*, or equivalent devices, so as to stay the sides of the hull properly for substantial construction, and in this space I propose to arrange a center-board, *i*, having slots *j*, through which the stay-bolts *d'* pass, the said slots allowing the center-board to be shifted up and down, as is required for such boards; but the bolts may be omitted in small vessels.

For the means of shifting the center-board up and down, I propose to incline the slots *j* forty-five degrees, or thereabout, to support about half the weight of the center-board on the bolts, so that by pulling the board backward with power equal to about half the weight of the center-board it will be raised up flush with the bottom of the vessel, or thereabout, and by releasing it it will slide forward and downward. A chain, *l*, pulley *m*, and lever *n*, or any equivalent device, may be used for raising the board, and a latch and notched quadrant or other device may be employed for holding it up. The center-board will be sufficiently shorter than the space *a* to allow of the lengthwise motion of the said board for so raising and lowering it. I also propose to make slots *o* in the center-board for all the stay-bolts *d'* in advance of the hindermost one, and connect a chain, *p*, with the forward end, to raise it on the sternmost bolt as a pivot, to facilitate the swinging of the bow around in making the tacks.

In order to prevent undue pressure on the

sternmost bolt, d' , by the overbalancing forward end of the center-board when in the lowermost position, and to avoid too much friction thereon at the beginning of the hoisting movement, I propose to attach friction-rollers 5 q to the center-board near its rear upper corner, and provide rails t on the partitions b for them to bear against to resist the upward thrust of the rear end. The stay-bolts d' are designed to carry friction-rollers u , to facilitate the working of the keel-board on them.

It will be seen that a center-board arranged on the stay-bolts d' by inclined slots, as I propose, will naturally rise and relieve the vessel of undue strains when it touches bottom, if hard, and I propose to attach a signal-bell, v , to be actuated by a rack, w , or any approved means, for giving warning at once of the danger at hand.

20 It will be seen that my improved contrivance affords a practical keel, with the advantage of the center-board arrangement, and it is a center-board without materially greater draft than the ordinary keel, and the rise in 25 the vessel is much less than the ordinary board rises. It is also much less subject to damage than the ordinary center-board.

20 In small vessels the partitions b , inclosing the center-board space, may be utilized for supporting seats x for passengers and crew.

I propose to vary the inclinations of the slots j proportionally to the required greater extension of the center-board at the stern than at the bow—that is, the angle of the rear slot will 35 be greatest and those forward will be less—so that for a given lengthwise movement of the board it will rise and fall as much more at the stern end than at the bow end as the difference in the desired projection of the board below the bottom from end to end, whereby, it 40 will be seen, the keel will bear the same proportionate relations to the vessel, no matter how much or little it may be let down, so that the weights attached to the lower edge for ballast 45 will not be changed relatively to the vessel, except in the degree of the extension of the keel and a slight change lengthwise, which is a material advantage as compared with those center-boards that swing up and down on one 50 end.

I desire it to be understood that I do not limit myself to the slotted arrangement of the keel-board for causing it to rise and fall, for it may have rollers or studs attached to the 55 sides and working on inclined ways attached to or formed in the sides of partitions b . These I consider as equivalent to the slots working on the bolts d' , and I mean to include them as

my invention, to be used either when the stay-bolts are or are not used.

Having thus described my invention, what I claim, and desire to secure by Letters Patent, is—

1. A center-board arranged, substantially as hereinbefore set forth, on two or more inclined ways, for being raised and lowered thereon, said ways being arranged in the center-board trunk, and ranging fore and aft of the ship on about forty-five degrees of inclination, for supporting about half the weight 65 of the center-board while being raised and lowered, in combination with a cord or chain connected to said center-board and stretched upward in about the same inclination as said ways, for raising and lowering said center-board by pulling about half the weight of the board, substantially as described.

2. A center-board arranged, substantially as hereinbefore set forth, on two or more inclined ways, for being raised and lowered, said ways being suitably inclined for supporting about 70 half the weight of the board throughout the range of its travel, the aft ways having greater 75 inclination than the forward ways, and being varied with relation to said forward ways, to cause the center-board to extend more aft than forward, and also to cause the said greater extension to be proportionately the same for any 80 extension of said center-board, substantially as described.

3. A center-board arranged on two or more inclined ways of about forty-five degrees, whereon about half its weight is supported, and being provided with curved ways or slots 85 o , intersecting the inclined ways that are forward of the sternmost way, to allow the center-board to be swung up at the forward end on the sternmost way, whereon it rests as a pivot, substantially as described.

4. In a center-board arranged on two or 90 more inclined ways of about forty-five degrees, whereon about half its weight is supported, the rollers q and ways t , in combination with the center-board, and located at one end of the center-board, to resist the thrust of the overbalance of the other end when the board shifts along said inclined ways, substantially as described.

In witness whereof I have hereunto signed my name in the presence of two subscribing 110 witnesses.

JOHN S. BIRCH.
